(57) **CLAIM**

The ornamental design for charger with camera, as shown and described.

DESCRIPTION

FIG. 1 is a front, right, and top perspective view of a charger with camera, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 2 comprising an USB interface.

The broken lines shown in the drawings are included for the purpose of illustrating portions of the charger with camera that form no part of the claimed design.
